Primary Examiner — Keli L Hill(74) *Attorney, Agent, or Firm* — Beeson Skinner Beverly, LLP(57) **CLAIM**

The ornamental design for an arrayable loudspeaker, as shown and described.

DESCRIPTION

FIG. 1 is a top front perspective view of an arrayable loudspeaker showing our new design;

FIG. 2 is a front elevational view thereof;

FIG. 3 is a cross-sectional view thereof taken along section lines 3-3 in FIG. 2; and,

FIG. 4 is a cross-sectional view thereof taken along section lines 4-4 in FIG. 2.

The broken lines shown in FIGS. 1 and 3-4 represent a cabinet for the arrayable loudspeaker; additional broken lines in FIG. 4 represent the backs of cone drivers of the arrayable loudspeaker. These broken lines form no part of the claimed design. The broken line rectangles at the front of the arrayable loudspeaker shown in FIGS. 1 and 2 represent boundary lines; the areas within the boundary lines contain unclaimed subject matter which forms no part of the claimed design.
